(57) **CLAIM**

The ornamental design for an insulated conductor as shown and described.

DESCRIPTION

FIG. 1 is a perspective view of an insulated conductor according to our new design; and,

FIG. 2 is a cross-sectional view taken along line 2-2 of FIG. 1.

The article is also shown with a symbolic break line in its length. The appearance of any portion of the article beyond the break line forms no part of the claimed design. The dash-dot broken lines indicate a cross-sectional view and form no part of the claimed design.
